UNITED STATES PATENT OFFICE

CLARK WHITE, OF ASHLAND, KENTUCKY

ROLLING MILL CONTROL

Application filed October 3, 1929. Serial No. 397,100.

This invention relates to improvements in rolling mills, and it consists of the constructions, combinations and arrangements herein described and claimed.

5 An object of the invention is to provide adjusting mechanism for rolling mills, which mechanism is electrical in its nature and capable of control from a single switchboard by a single operator to perform a simultaneous right or left shift of one end of the supporting rolls to produce a roll alinement, or to either simultaneously shift the supporting rolls towards each other or simultaneously away from each other, to produce a sheet thickness 15 adjustment.

A further object of the invention, and one in direct agreement with the foregoing statement, is to make a special provision of mechanism in a rolling mill for shifting the bottom 20 working roll in a number of ways in respect to the top working roll so that the strip or sheet thickness can be regulated with precision.

25 A further object of the invention is to provide a mechanism by the use of which it is possible to adjust the mill rolls for both sheet thickness and roll alinement.

Other objects and advantages will appear 30 in the following specification, reference being had to the accompanying drawings, in which:—

Fig. 1 is a diagram of a typical rolling mill installation.

35 Fig. 2 is a diagram of one form of switchboard for one of the stands of rolls.

Fig. 3 is a diagram of a central station switchboard showing how the switches of all 40 of the stands of rolls can be combined so as to be under the supervision and control of a single operator.

Fig. 4 is an end elevation of one of the stands of rolls, particularly illustrating the mechanism by which the supporting rolls and the bottom working roll are adjusted.

45 Fig. 5 is a detail vertical section taken on the line 5—5 of Fig. 4.

Fig. 6 is a vertical section of the dual electro-magnetic clutch hereinafter described.

50 Fig. 7 is a vertical section of the companion single electro-magnetic clutch.

Fig. 8 is a side elevation of one of the breaker switches used in conjunction with the electro-magnetic clutches.

Fig. 9 is a plan view of the breaker switch.

Fig. 10 is an elevation of one of the magnetic brakes as viewed on the line 10—10 of 55 Fig. 4.

Fig. 11 is an elevation of one of the lock-out switches used in conjunction with both the magnetic brakes and the directional power 60 switch later described.

Fig. 12 is a plan view of said directional power switch.

Fig. 13 is an elevation of one end of said switch. 65

Fig. 14 is a plan view of one of the relays.

Fig. 15 is an elevation of one end of the relay, the box being shown in section.

Fig. 16 is a front elevation of the interrupter switch. 70

Fig. 17 is a side elevation of said switch.

Fig. 18 is a diagram of the electrical wiring involved in the control of the apparatus.

Fig. 19 is a partial sectional and elevational view of the uni-directional device illustrated 75 in Fig. 4.

Fig. 20 is a cross-section taken on the line 20—20 of Fig. 19.

This invention is an improvement on the rolling mill disclosed in an application for 80 patent filed by Clark White, February 25, 1928, Serial No. 257,081, to which recourse may be had for such details as the means for driving the various rolls as well as an exposition in detail of the causes of the production 85 of scrap.

A typical rolling mill assemblage is illustrated in Fig. 1 in which the stands of rolls 1, 2, 3 and 4 are arranged to reduce a sheet or strip of metal 5 to the desired thickness prior 90 to winding the sheet upon a mandrel or drum 6.

Briefly described, the structure, for example, of the stand 1, is as follows: The roll housing comprises a base 7 which has an upright 8 at each end, the base and uprights providing the supports for bearing blocks 9 and 10 by which bottom and top supporting rolls 11 and 12 are respectively carried. The drawings show only the near upright and one 95 100

set of adjusting mechanism for the near ends of the bottom supporting rolls, but it is to be understood that the structure, including the set of adjusting mechanism, is duplicated at the unseen end of the base.

Situated between the bottom and top pairs of supporting rolls are working rolls 13 and 14. The work, previously identified as the sheet 5, passes between these rolls, and it is by the manipulation which the bottom supporting rolls 11 are capable of that the bottom working roll 13 is so set in respect to the top working roll 14 as not only to reduce the work to the desired thickness, but also cause it to traverse a true forward course.

The bearing blocks 10 of the top supporting rolls 12 are fixed upon the upright 8, but the bearing blocks 9 of the bottom supporting rolls are movable upon the base 7, these bearing blocks being capable of being simultaneously moved to the right or left (Fig. 4), simultaneously toward each other or simultaneously away from each other. It is observed that the bottom working roll 13 is supported in the trough of the bottom supporting rolls, as is also the top working roll in respect to the top supporting rolls 12, hence, any adjustment of the bottom supporting rolls will affect the position of the bottom working roll 13 in relationship to the top working roll 14.

The manner in which the bottom supporting rolls 11 are shifted in the various ways outlined above is as follows: Mill screws 15 and 16, appropriately supported by the upright 8, back or abut the bearing blocks 9. Each of these screws has a right-hand thread. The outer end of the screw 15 carries a gear 17 which meshes with a pinion 18 which is slidably mounted upon the component 19 of a power shaft, the other component 20 of which slidably carries a pinion 21 which meshes with a gear 22 on the outer end of the mill screw 16. The gears 17 and 22 are identical in pitch-diameter, as are also the pinions 18 and 21, although the gears are larger than the pinions. The slidable connection of the pinions with the power shaft is produced either by squaring portions of the components 19 and 20 or providing them with some other known expedient for insuring rotation yet permitting the necessary sliding motion of the pinions.

An electric motor 23, designed to run at about 600 R. P. M., has a gear train associated with each end of its shaft. The gear train at the left end (Fig. 4) comprises a pinion 24, idler 25, and gear 26. The gear train at the right comprises a pinion 27, idlers 28, 29 and a gear 30. It also includes a connected gear and pinion 31 and 32, which latter meshes with and drives a so-called spacer control gear 33.

The gear 26 is a part of a dual electro-magnetic clutch 34, the details of which are shown in Fig. 6, while the gear 30 is a part

of a single electro-magnetic clutch 35, the details of which are shown in Fig. 7. The left gear train (Fig. 4) operates the components 19 and 20 of the power shaft as one when the dual clutch 34 is energized, thus to feed both mill screws to the right and cause a simultaneous shifting of the near ends of the bottom supporting rolls 11 to the right.

A reversal of the motor 23 will cause a reverse shifting of the bottom supporting rolls 11 by means of the left gear train. An operation of the right gear train by the forward rotation of the motor 23 with the clutch 35 energized and the clutch 34 de-energized, will feed the screw 15 to the right and the screw 16 to the left, causing shifting of the supporting rollers 11 toward each other and the elevation of the bottom working roll 13. A reversal of the motor 23 will cause a reverse feeding of the screws 15 and 16 and a simultaneous outward shifting of the near ends of the supporting rolls 11, thus to lower the bottom working roll 13.

That structure of the electro-magnetic clutches is as follows: The hub 36 (Fig. 6) of the clutch 34 contains an electro-magnet 37 in position to attract an armature 38 which is carried by a spring plate 39. The spring plate is mounted upon a collar 40 which is secured to the shaft component 20 by a pin 41 or its equivalent. The hub 36 is secured to the shaft component 19 by a pin 42. The confronting ends of the components 19 and 20 which, it will be understood are separate, meet at a short plug 43 which merely establishes the continuity of the power shaft and, in a measure, serves as a bearing at the point between the clutch elements which the hub 36 and collar 40 comprise.

A lining 44 on the peripheral flange 45 of the hub 36 provides both a gripping surface for the armature 38 as well as a check to prevent the adhesion of the armature to the hub or the electro-magnet by magnetic attraction. An extension 46 of the hub 36 carries collector rings 47 with which the terminals of the magnet 37 as well as the feed wires of the electro-magnet are connected by means of brushes. A circular flange 48 on the periphery of the armature 38 serves the sole purpose of actuating a breaker switch 49 illustrated in detail in Figs. 8 and 9.

This breaker switch, a duplicate of which is used in connection with the clutch 35 (Fig. 7), serves the purpose of insuring the energization of only one of the electro-magnetic clutches at one time. These switches work in conjunction with certain lock-out switches (Fig. 11) of the directional power switches in Figs. 12 and 13 to control the circuits of the motor 23, and to that end act as starter buttons. The switch 49 comprises a pivoted arm 50 having a roller 51 bearing against the flange 48 by virtue of the tension of the springs 52 which, at their oppo-

site ends, are connected to the insulated switch base 53 and blades 54, 55. Contacts 56, 57 on the base coat with the blades 54, 55, while angled extensions 58, 59 of said blades coat with contacts 60, 61 also on the base. The blades are in electrical connection but in practice the arm 50 is suitably insulated therefrom.

Reference is now made to the single electro-magnetic clutch 35 (Fig. 7). It comprises a hub 62 which is loose on the shaft component 20. The hub carries an electro-magnet 63 capable of attracting an armature 64 carried by a spring plate 65 on a collar 66 pinned to the component 20 at 67. The armature has a circular flange 68 for the purpose of actuating the duplicate of the breaker switch 49, which, for the purpose of the later description, has contacts 56^a, 57^a, 60^a, 61^a, as well as blades 58^a, 59^a (Fig. 18). A lining 69 on a peripheral flange 70 of the hub 62 serves the same purpose in respect to the armature 64 as does the lining 44 in respect to the armature 38. An extensor 71 of the hub carries collector rings 72 of which the brushes of the magnet terminal and the feed wires thereof bear.

It is to be noted in Figs. 6 and 7 that the hubs and collars abut. This fixes the relationship of the electro-magnets to the armatures. Since these must be disengaged when the clutches are de-energized, it follows that the plates 39 and 65 must be resilient in nature. The energization of either magnet 37 or 63 will attract the corresponding armature and cause a shifting of the associated breaker switch 49 from the position shown in Figures 6, 7 and 8.

The shaft components 19 and 20 have magnetic brakes 73 and 83. The purpose of the electro-magnetic brakes is to prevent screw drift when the mill is in operation, holding the screws immovable unless they are actuated by the motor 23 in an adjusting operation. These brakes are identical in construction and operation and the following mechanical description of the brake 73 (Fig. 10) will suffice for both: Each of a pair of brake shoes 74, pivoted at 75 to a fixed support, has a lining bearing on a drum 76 fixed on the respective shaft component. A spring 77, connected with the otherwise free ends of the shoes 74, draws them toward each other when permitted, thus to apply the brakes to the shaft components 19 and 20 when the electrical parts are de-energized. The upper shoe pivotally carries a lever 78 with which links 79 and 80 join. The link 79 is connected with a pivoted armature 81. The link 80 has connection with the lower shoe 74, and when the electrical part of the brake is energized the action is to separate the shoes and release the respective shaft component. A stop 82

adjoining one of the shoes 74, limits the motion of each.

Although the electrical parts of the magnetic brakes are identical, they must be separately identified for the purpose of the description of the circuits in Fig. 18. The brakes 73 and 83 have electro-magnets 84, 85 in position to attract the respective armatures 81. Upon attraction of the armatures, the action is to lift the links 79 and by the combined lifting and pivotal action upon the levers 78 to rock the brake shoes 74 in opposite directions against the tension of the springs 77, thus to release the shaft components 19 and 20. Lock-out switches 86 and 87 embodied in the brakes 73 and 83, respectively, have contacts 88, 89 and 90, 91 which are closed when the brakes are de-energized and applied and opened when the brakes are energized and released.

The description of one of the lock-out switches is as follows: A plate 92 (Fig. 11) has a flange 93 which at once guides a stem 94 and provides an abutment for one end of a spring 95. The other end of the spring 95 bears against a contactor 96 carried by the stem. This contactor bridges the contacts 88 and 89 (using the lock-out switch of the brake 73, for example) when the spring 95 is free to act. The contacts are carried by an insulating block 97. The upper end of the stem 94 has an eye 98 at which it is pivotally suspended.

Reference has been made to the spacer control gear 33. The purpose of this gear 100 is to control the period of energization of one of the clutches 34, 35 and of the motor 23, hence the period of adjustment of the bottom supporting rolls 11. A cycle of adjustment operations is embraced by one revolution of the spacer control gear. The ratio of the gear train between the motor 23 and gear 33 (Fig. 4) is such that the gear 33 will complete one revolution when the mill screws 15 and 16 have moved .001 of an inch, 110 which extent of movement is herein used as the example. By a proper design of the gear trains between the motor 23 and the components 19, 20 of the power shaft, the extent of movement of the screws 15 and 16 115 may be as small as .0005 of an inch.

An interrupter switch comprising an arm 99 (Figs. 16 and 17) pivoted at 100 has suitably insulated therefrom a contactor 101 intended to engage contacts 102, 103 in a circuit-closing position during a cycle of operation. It is by means of the interrupter switch that any one of a bank of four relays 104, 105, 106, 107 is maintained in a circuit-closing position during a cycle of adjustment. It is also by means of the interrupter switch that said relays are rendered inoperative so that the cycle of operation ends precisely when the adjustment has been made. For the latter purpose, the gear 33 actuates

a lug 108 that is engageable with the near end of the arm 99 to rock the arm on its pivot when the gear has completed one revolution, thus to momentarily move the contactor 101 to a circuit-opening position. 5 Springs 109 keep the arm 99 in a balanced or circuit-closing position at all times excepting when the arm is shifted by the lug.

The gear 33 (Figs. 4, 5 and 19) is necessarily uni-directional in its rotation so that the lug 108 may always function the same in respect to the switch arm 99. This is accomplished by a uni-directional device 243 comprising a pair of disks 244, 245 and an intermediate body 246 to the periphery of which a ratchet 247 is carried. The gear 33, disk 244 and internal gear 248, which is a counterpart of the gear 33, are either secured to or integral with a shaft 249 upon which the disk 245 and body 246 are loosely journaled to the extent that motion relative to the shaft is possible upon a reversal of the motor 23.

A spring 250, mounted on a reduced extension of the shaft 249, bears against a washer 251 on said extension and against the outer face of the disk 245, thus pressing the disk 245 and body 246 together and, in turn, against the disk 244. A second internal gear 252, which is attached to the disk 245 and 30 is a counterpart of gears 33 and 248, meshes with one of a pair of meshing reversing idlers 253, 254, the other one of which meshes with the gear 248. The idlers are suitably journaled upon the body 246 and with the exception of the meshing engagement with the gears 248 and 252 have no other connection with the disks 244, 245, excepting a possible sliding contact, as will probably occur in the assemblage of the device.

40 A dog 255 (Fig. 20) stands in a position to engage the ratchet 247. It is pivoted at 256 upon a suitable support, and the same support may be used as the mounting for one end of a spring 257, the other end of which is attached to the dog for the purpose of keeping the dog in engagement with the ratchet. Forward rotation of the motor 23 will cause a bodily forward motion of the uni-directional device 243 away from the dog 255 during which time the gears 253, 254 will be idle. A reversal of the motor will cause the dog to hold the body 246, bringing the reversing idlers 253, 254 into play to turn the disk 245 in the direction opposite to that in which the 55 gear 33 will be turning. But the reversing action of the idlers will be to turn the disk 245 in the same direction as originally; in other words, the lug 108 will move forwardly in either direction of the motor.

60 Each relay of the bank of relays is identical in construction, but since each must be described separately for the purposes of the wiring diagram in Fig. 18 as well as the summary of the operation, it is necessary to independently designate the various parts as fol-

lows: Relay 104 has a movable armature which carries contactors 110, 111, 112 which are engageable with contacts 113, 114, 115 when the armature is attracted by an electromagnet 116.

70 On the same principle, relay 105 has contactors 117, 118, 119 which are engageable with contacts 120, 121, 122 when an electromagnet 123 is energized. In the relay 106 contactors 124, 125, 126 are engageable with contacts 127, 128, 129 when an electro-magnet 130 is energized, and in relay 107 the energization of electro-magnet 131 attracts an armature which carries contactors 132, 133, 134 which then engage contacts 135, 136, 137.

75 Briefly referring to Figs. 14 and 15, which illustrate, for example, the details of relay 104, an armature 138 is pivoted at 139 and held by a spring 140 in a position of disengagement of the armature from the electromagnet 116 and the contactors 110, 111, 112 from the contacts 113, 114, 115. The relay parts are appropriately mounted in a box 141.

80 Mention has been made of a directional power switch. This is designated 142 in Figs. 90 12, 13 and 18. Its purpose is to so conduct current to the motor 23 that the motor will revolve either forwardly or reversely. It comprises rockers 143, 144 which respectively carry contactors 145, 146, 147, 148, 149, 150 for engagement with sets of contacts 151, 152, 153, 154, 155, 156. The rocker 143 has an armature 157 and an electro-magnet 158 by which it is operated in one direction. The rocker 144 has an armature 159 and an electro-magnet 160 for the same purpose.

85 Lock-out switches 161, 162, identical in construction with the showing in Fig. 11, control pairs of contacts 163, 164, 165, 166. These switches are closed when the electro-magnets 158, 160 are de-energized and the directional power switch is open. The energization of either electro-magnet and the consequent rocking of the respective rocker will close a power circuit through the motor 23 and simultaneously open the respective lock-out switch, thus to avoid any possibility of closing a conflicting circuit through the motor.

90 Upon energization of the electro-magnet 158 the switch components of the rocker 143 control the passage of current for the forward rotation of the motor 23, the continuity of the circuit through the electro-magnet 158 being established by the then closed lock-out switch 162 of the then inactive side of the power switch 142. The lock-out switch 161 is opened by the rocker 143 when its contactors and contacts are engaged to close that circuit through the motor which causes forward rotation. This opening of the switch 161 prevents the passage of current to the electro-magnet 160 of the inactive side of the power switch, in turn preventing rocking of the rocker 144 and the closure of that cir- 100 110 115 120 125 130

cuit through the motor which will cause reverse rotation.

The electrical circuits embrace the following wiring: Attention is directed to Fig. 18.

- 5 Two main switches 167, 168 are employed. These control the passage of current from separate sources, although in practice a single current source may be made to suffice. The current which the main switch 167 controls is 10 supplied to the electro-magnetic clutches 34, 35 and to the breaker switches 49 thereof, to the lock-out switches of the magnetic brakes, to the bank of relays 104, etc., as well as to the electro-magnets of the directional power 15 switch 142. The main switch 168 controls the supply of current to the motor 23 and to the magnetic brakes 73, 83. Positive wires 169, 170 and a common negative wire 171 are connected with the terminals of the switch 20 167, while positive wires 172, 173 and a common negative wire 174 are connected with the terminals of the switch 168. Wire 169 is connected with one contact 90 of the lock-out 25 switch 87, the other contact 91 of this switch being connected by means of a wire 175 with the contact 88 of the lock-out switch 86. The other contact 89 of this switch is connected by means of a wire 176^a with the back contacts 176, 177, 178, 179 of switches 180, 181, 30 182, 183. These switches have common connection by means of wires 184, 185, 186, 187 with the contactors 110, 117, 124, 132, as well as with one terminal of each of the electro-magnets 116, 123, 130, 131 of the respective 35 relays 104, etc.

- A wire 225 has branches 226, 227, 228, 229 to the other terminals of the electro-magnets 116, etc. The common negative wire 171 joins the wire 225 by having a connection at 189 40 with its branch 226. An emergency stop button 190 is connected in the common negative return, the wires 171, 189 being connected with the contacts 192, 191 of this switch. The switch is normally closed, and a depression 45 of it at any time within a period of adjusting operations will instantly stop the adjusting mechanism.

- Connected with wire 169 at a point 193 is a wire 194 that joins contact 102 of the interrupter switch. The other contact 103 of this switch has a connected wire 194^a with which branches 195, 196, 197, 198 of contacts 113, 120, 127, 135 of the relays 104, etc., are joined. A wire 199 connects point 193 with contacts 50 55 60, 60^a of the breaker switches 49. The companion contacts 61, 61^a are connected by a wire 200 which has connected thereto a wire 201 with branches 202, 203 to one terminal of each of the electro-magnets 158, 160 of 60 the power switch 142. The other terminal of the electro-magnet 158 is connected by means of a wire 204 with contact 165 of the lock-out switch 162, while the other terminal of the electro-magnet 160 is connected by means of 65 a wire 205 with the contact 163 of the lock-out

switch 161. The remaining contact 166 of the lock-out switch 162 is connected by a wire 206 and branches 207, 208 with contacts 115, 129 of relays 104, 106. The remaining contact 164 of the lock-out switch 161 is connected by means of a wire 209 and branches 210, 211 with contacts 122 and 137 of relays 105, 107.

The positive feed wire 170 connects with one terminal of the electro-magnet 37 of clutch 34 and by means of a branch 212 with one terminal of electro-magnet 63 of clutch 35. The other terminal of electro-magnet 37 is connected by means of a wire 213 with contact 56^a, while the remaining terminal of electro-magnet 63 is connected by means of a wire 214 with contact 56. Contact 57^a has connection by means of a wire 215 and branches 216, 217 with contacts 114 and 121 of relays 104, 105. Contact 57 has connection by means of a wire 218 and branches 219, 220 with contacts 128, 136 of relays 106, 107. Branches 221, 222, 223, 224 make common connection of the wire 225, previously mentioned, with the pairs, 111, 112; 118, 119; 25 125, 126, and 133, 134 of relays 104, etc.

Wires 230, 231, 232 connect contacts 151, 152, 153 of the switch 142 with the terminals of the motor 23. Branches 233, 234, 235 connect the respective wires with the contacts 156, 155, 154 of the switch 142. Other branches 236, 237 connect wires 230, 232 with wires 238, 239 which serve as common connectors for the terminals of the electro-magnets 84, 85 of the brakes 73, 83. These electro-magnets are energized simultaneously with the motor 23 during rotation of the latter in either direction, thus to hold the brakes in the released positions.

The operation

is as follows: Bear in mind that the components 19 and 20 of the power shaft are separate. The confronting ends meet at the plug 43 between the elements of the dual electro-magnetic clutch 34 (Fig. 6). It is to the respective parts of the power shaft that the elements 36 and 40 are connected. Respecting the electro-magnetic clutch 35, the element 62 is loose on the component 20 while the element 66 is connected thereto. The electro-magnets 37, 63 of the clutches 34, 35 are de-energized when the adjusting mechanism is inactive. This is also true of the electro-magnets 84, 85 of the brakes 73, 83 for the same period. Both brake electro-magnets 84, 85 are energized simultaneously with one or the other of the clutch electro-magnets 37, 63. The clutch electro-magnets are energized individually and at no time are both energized together.

To shift the bottom supporting rolls 11 simultaneously to the right: A primary or starting circuit is closed by the closing switch 180. Current flows from the positive pole of 130

the source of current over wire 169, contacts 90, 91 of the lock-out switch 87, wire 175 and contacts 88, 89 of the lock-out switch 86, wire 176^a, back contact 176 of switch 180, wire 184, 5 electro-magnet 116, wires 226, 189, contacts 191, 192 of stop button 190 and wire 171 to the negative pole of the source of current. The energization of the electro-magnet 116 attracts the armature 138 (Figs. 14 and 15) 10 of relay 104, engaging contactors 110, 111, 112 with contacts 113, 114, 115.

A secondary or holding circuit is closed by the attraction of the armature 138 as follows: Positive current flowing along wire 15 169 divides at point 193, a portion traversing wire 194, contacts 102, 103 of the interrupter switch, wire 194^a, branch 195, contact 113, contactor 110, electro-magnet 116, wires 226, 189, 171 to the negative pole of the source of 20 current. Since the electro-magnet 116 is energized through a second circuit, the operator may release the switch 180, whereupon the remaining adjusting operation will be entirely automatic. When the need for an 25 adjustment arises, the operator has only to close the switch 180, or any other switch in the same series, and instantly remove his finger, whereupon the adjusting operation will proceed of its own accord. The closure 30 of the secondary circuit maintains the energization of the electro-magnet 116 and the retention of the armature 138 in the attracted position.

A third or clutch circuit is closed as follows: Current from the positive pole of the 35 source of current traverses wire 170, electro-magnet 37 of clutch 34, wire 213, contacts 56^a, 57^a and blades 58^a, 59^a of the breaker switch 49 of clutch 35, wire 215, 40 branch 216, contact 114, contactor 111, branch 221, wires 226, 189, 171 to the negative pole. The energization of electro-magnet 37 attracts armature 38 (Fig. 6), locking the components 19, 20 of the power shaft together. 45 The motion of armature 38 shifts breaker switch 49 of clutch 34, closing the switch at contacts 60, 61 and opening it at contacts 56, 57.

A fourth or power switch circuit is closed 50 as follows: A portion of the positive current of wire 169 divides at point 193 and traverses wire 199, contacts 60, 61 and blades 58, 59 of the breaker switch 49, wire 201, branch 202, electro-magnet 158, branch 204, 55 contacts 165, 166 of lock-out switch 162, wire 206, branch 207, contact 115, contactor 112, branch 221 and wires 225, 226, 189, 171 to the negative pole. The energization of electro-magnet 158 attracts armature 157, moving 60 the forward rocker 143 to engage its contactors with the complementary contacts.

Fifth and sixth motor and brake release circuits are closed as follows by the active part 65 of power switch 142: Current from the positive pole of the source of current traverses

wire 173, contactor 147, contact 153, wire 232, motor 23, wire 230, contact 151, contactor 145, returning to the negative pole by way of wire 174. A division of the current occurs at wire 236, flowing over wire 238 to electro-magnets 84, 85 of brakes 73, 83, returning by way of wires 239, 237 to the source of current. The simultaneous energization of electro-magnets 84, 85 attracts armatures 81, thus releasing brakes 73, 83 from shaft components 19, 20. 70 The power shaft is thus free to be turned by the motor 23 which is regarded as running forwardly.

Driving power is applied to gear 26 of clutch 34. Gear 30 of clutch 35 runs idle because its electro-magnet 63 is de-energized. Shaft components 19, 20 revolve as a single unit in the direction of the arrow in Fig. 4. The gears of the trains connecting the shaft with the mill screws 15, 16 revolve as indicated, causing movement of the mill screws in one direction and simultaneous shifting of the ends of the supporting rolls 11 to the right.

Spacer control gear 33 begins rotation with the operation of the motor 23. The uni-directional device 243 will operate thus: Gear 33 will turn in the direction of the arrow in Fig. 19. The disks 244, 245 and body 246 are held together by the spring 250 and the device will 90 bodily turn in the same direction (Fig. 20) and the lug 108 in the correspondingly forward direction (Fig. 16). The ratchet 247 will slip past the dog 255. Bear in mind that the secondary or holding circuit of relay 104 100 relies upon the engagement of contactor 101 with contacts 102, 103 of the interrupter switch. As soon as gear 33 has completed one revolution, which represents a cycle of 105 adjusting operation, lug 108 will engage and momentarily move arm 99 to open the interrupter switch. This de-energizes electro-magnet 116, permitting the return of armature 138 by means of spring 140 (Fig. 15) and the opening of all of the circuits depending upon relay 104 for closure. The return of armature 38 of clutch 34 (Fig. 6) to the original position permits the return of the associated breaker switch 49 to the original position shown in Fig. 18. The stop 110 button 190 is for the purpose of enabling the operator to stop the adjusting operation at any point in the foregoing cycle. This button is in position to control the return flow of current from any of the bank of relays. Obviously, the opening of switch 190 will have the same effect as the momentary opening of the interrupter switch, the only difference being that switch 190 is operated manually 115 and is capable of operation at any time within the cycle of adjusting operations.

For shifting both supporting rolls 11 to the left: Close switch 181. Current flows from positive wire 169, through lock-out switch 87, wire 175, lock-out switch 86, wire 120

- 176^a, back contact 177, switch 181, branch 185, electro-magnet 123, branch 227, wires 225, 226, 189, switch 190 and wire 171 to the negative pole of the source of current. Energization of electro-magnet 123 actuates relay 105 in the precise manner described in respect to relay 104. The secondary or holding circuit is established through the interrupter switch at contact 120 and contactor 117 as before. The third or clutch circuit is established at contact 121 and contactor 118 as before. The same electro-magnet 37 is energized and clutch 34 rendered operative to couple shaft components 19 and 20 together. The fourth or power switch circuit is now closed as follows: A portion of the positive current of wire 169 divided at point 193 traverses wire 199, the contacts and contactors of the now closed breaker switch 49 of clutch 34, wire 201, branch 203, electro-magnet 160, branch 205, contacts 163, 164 of lock-out switch 161, wire 209, branch 210, contact 122, contactor 119, branch 222, wires 225, 189, 171 to the negative pole of the source of current. It is the closure of the circuit at contact 122 that diverts the current in wire 201 to the reverse component of power switch 142.
- Energization of electro-magnet 160 causes turning of rocker 144 and the engagement of contactors and contacts to close a reverse circuit through the motor 23 as follows: Current flows from positive wire 173 to branch 233 and wire 230 to the motor, returning by way of wire 232, branch 235 and common negative wire 174. Current for the simultaneous energization of electro-magnets 84, 85 of brakes 73, 83 is derived as before. Motor 23 is operated in the reverse direction. The various active gear trains in Fig. 4 are operated in directions reverse to the showing of the arrow. Gear 33 turns opposite to the arrow in Fig. 19. The tendency is to correspondingly turn the entire uni-directional device, but the dog 255 holds the body 246, causing the idlers 253, 254 to function. The effect is to again turn the disk 245 forwardly (Fig. 20) and move the lug 108 (Fig. 16) forwardly in the direction of the arrow. Mill screws 15 and 16 are rotated in reverse directions causing simultaneous shifting of the ends of supporting rolls 11 to the left. The interrupter switch is momentarily opened after one revolution of the gear 33, thus stopping the adjusting operation.

For shifting the supporting rolls 11 in opposite directions or toward each other: The closure of switch 182 causes completion of the primary or starting circuit and the secondary or holding circuit, but this time, clutch 35 is brought into action. Current from the positive wire 170 traverses branch 212, electro-magnet 63 of clutch 35, wire 214, the contacts and contactors of breaker switch 49 of the now inactive clutch 34, wire 218, branch 219, contact 128, contactor 125, branch 223 and wires 225, 226, 189, 171 to the negative pole of the source of current. Electro-magnet 63 attracts armature 64 (Fig. 7), securing the previously loose clutch element 62 to shaft component 20. Bear in mind that shaft component 19 remains disconnected from component 20. Rotation of the motor 23 will produce opposite rotations of components 19 and 20 and, in turn, rotate mill screws 15 and 16 in opposite directions thus to feed them oppositely and produce opposite shiftings of the supporting roll ends. Attraction of armature 64 (Fig. 7) caused a shifting of the associated breaker switch 49, closing a circuit as follows: A division of positive current from wire 169 at point 193 traverses wire 199, contacts and contactors of said switch 49, wire 200, branches 201, 202, electro-magnet 158, branch 204, contacts 165, 166 of lock-out switch 162, wire 206, branch 208, contact 129, contactor 126, branch 223, and wires 225, 189, 171 to the negative pole of the source of current.

Energization of electro-magnet 158 causes operation of the forward component of power switch 142, directing current through the motor 23 in that direction which will cause it to rotate forwardly. By tracing the directions of rotation of all of the gear trains shown in Fig. 4, it will be seen that the mill screws 15 and 16 will be fed inwardly and the ends of supporting rolls 11 moved toward each other. Brakes 73, 83 are rendered inactive as before, and the cycle of adjusting operations is terminated by the actuation of the interrupter switch unless previously terminated by the opening of switch 190 by the operator.

For shifting the supporting rolls away from each other: Closure of switch 183 causes energization of electro-magnet 63 of clutch 35 and renders inoperative the brakes 73, 83 as before. The same secondary or holding circuit is closed, this time at contact 135 and contactor 132 of relay 107. But the engagement of contact 137 by contactor 134 closes a circuit through reverse electro-magnet 160. Current is directed to the motor 23 in the reverse direction, causing a reverse rotation of the motor as well as of all of the gear trains in Fig. 4. The mill screws 15 and 16 are thus fed outwardly and the ends of the supporting rolls 11 are separated from each other.

It will bear repetition that all of the foregoing adjustments are performed on the near ends of the supporting rolls 11 of one stand of rolls. Similar adjusting mechanism will be employed on the remote and unseen ends of the supporting rolls. Since this duplicate control must also be under observation of the operator it follows that the switchboard 240 (Fig. 2) may be divided at 241 to

contain two sets of buttons. The set at the left represents the switches 180, etc. The set at the right represents corresponding switches for the remote control. The various buttons will be arranged on the switch-board in a manner regarded most suitable, the showing in Fig. 2 merely being for the purpose of illustration.

Since each of the stands of rolls in Fig. 1 must have an individual control, and since the controls for both the near and remote ends must be taken into account, the mode of placing all under the supervision of a single operator will be carried out as indicated in Fig. 3.

15 Here the central station switchboard 242 is divided into four panels, each representing one of the stands of rolls. The arrangement of buttons on these panels will be the same as shown in Fig. 2.

20 The previously described simultaneous shifting of the supporting rolls 11 to the right or to the left produce adjustments of the working roll alignment. It is by this means that one end of the bottom working roll 13 is adjusted in either lateral direction in respect to the top working roll 14. The simultaneous shifting of the supporting rolls 11 toward or away from each other control the sheet thickness. When the supporting rollers are moved toward each other the trough between the rollers is lessened and the bottom working roll 13 is caused to move in the vertical direction, thus affecting the sheet thickness. When the supporting rolls are 30 moved away from each other, the trough is deepened, permitting the bottom working roll 13 to sink lower, again affecting the sheet thickness. In the first instance, the sheet is rolled thinner, while in the second instance, a 35 thicker sheet is produced.

35 Regardless of the direction of the motor 23, the uni-directional device 243 will cause the lug 108 to move in the forward direction (Fig. 16) only. Upon completion of a revolution of the spacer control gear 33, the lug 108 will assume a position immediately beside the switch arm 99. Were it not for the provision of the uni-directional device, the reversal of the motor 23 would reverse the 40 direction of movement of the lug 108 and immediately open the interrupter switch thus frustrating the intent of the operator. The reader will understand that in the so-called forward directions of the motor 23 the entire 45 uni-directional device will turn with the gear 33 as one, but upon reversal of the motor there will be a slippage between the then stationarily held body 246 and the disk 245 so that the idlers 253, 254 may function to 50 turn the disk 245 in the forward direction which is contrary to the then reverse rotation of the disk 244.

55 While the construction and arrangement of the improved rolling mill control is that of a generally preferred form, obviously modifi-

cations and changes may be made without departing from the spirit of the invention and the scope of the claims.

I claim:—

1. In a rolling mill having a working roll and a pair of supporting rolls; abutment means receiving the separating thrusts of the supporting rolls, adjusting mechanism for feeding the abutment means either simultaneously in one or the other direction or simultaneously in diverse directions, said mechanism including a two-part power shaft, an electro-magnetic clutch having its elements secured to the respective parts of the power shaft, another electro-magnetic clutch having its elements respectively loose and secured to one part of the power shaft, means for driving one of the elements of each of the clutches, and electrical means for selectively energizing one or the other clutch while simultaneously actuating the driving means. 70

2. In a rolling mill having a working roll and a pair of supporting rolls; screws receiving the separating thrusts of the supporting rolls, adjusting mechanism for the screws including a two-part power shaft, an electro-magnetic clutch having its separated elements secured to the respective parts of the power shaft, means for driving one of the elements of the clutch, and electrical means for energizing said drive means and the clutch to attract its elements into gripping engagement thus to simultaneously turn the screws in one direction. 75

3. In a rolling mill having a working roll and a pair of supporting rolls; screws receiving the separating thrusts of the supporting rolls, adjusting mechanism for the screws including a two-part power shaft, an electro-magnetic clutch having its separated elements secured to the respective parts of the power shaft, means for driving one of the elements of the clutch, electrical means for energizing said drive means and the clutch to attract its elements into gripping engagement thus to simultaneously turn the screws in one direction, and means prescribing a cycle of adjustment operation and automatically de-energizing the drive means and clutch at the end of said cycle. 80

4. In a rolling mill having a working roll and a pair of supporting rolls; screws receiving the separating thrusts of the supporting rolls, adjusting mechanism for the screws including a two-part power shaft, an electro-magnetic clutch having its separated elements secured to the respective parts of the power shaft, means for driving one of the elements of the clutch, electrical means for energizing said drive means and the clutch to attract its elements into gripping engagement thus to simultaneously turn the screws in one direction, means prescribing a cycle of adjustment operation and automatically de-energizing the drive means and clutch at 85

the end of said cycle, and means for de-energizing said drive means and clutch during the performance of said cycle thus curtailing the adjustment operation.

5. In a rolling mill having a working roll and a pair of supporting rolls; abutment means receiving the separating thrusts of the supporting rolls, a power shaft with connections for feeding the abutment means in one direction, a motor for driving the shaft and having an electro-magnetic power switch controlling the flow of current thereto, an electro-magnetic clutch for connecting the motor with the shaft, and an electrical control comprising a circuit including the clutch, a circuit including the power switch, a relay energizable to complete said circuits, and a holding circuit completed by the relay for maintaining the energization of the relay and thus the closure of said circuits.

6. In a rolling mill having a working roll and a pair of supporting rolls; abutment means receiving the separating thrusts of the supporting rolls, a power shaft with connections for feeding the abutment means in one direction, a motor for driving the shaft and having an electro-magnetic power switch controlling the flow of current thereto, an electro-magnetic clutch for connecting the motor with the shaft, an electrical control comprising a circuit including the clutch, a circuit including the power switch, a relay energizable to complete said circuits, a holding circuit completed by the relay for maintaining the energization of the relay and thus the closure of said circuits, and means actuated by the motor after a period of operation for opening the holding circuit.

7. In a rolling mill having a working roll and a pair of supporting rolls; abutment means receiving the separating thrusts of the supporting rolls, a power shaft with connections for feeding the abutment means in diverse directions, a motor for driving the shaft and having an electro-magnetic power switch controlling the flow of current thereto, an electro-magnetic clutch for connecting the motor with the shaft, and an electrical control comprising a circuit including the clutch, a circuit including the power switch, a relay energizable to complete said circuits, and a holding circuit completed by the relay for maintaining the energization of the relay and thus the closure of said circuits.

8. In a rolling mill having a working roll and a pair of supporting rolls; abutment means receiving the separating thrusts of the supporting rolls, a power shaft with connections for feeding the abutment means simultaneously in either one of opposite directions, a motor for driving the shaft, a power switch having separate electro-magnetic means for controlling the flow of forwardly and reversely driving current to the motor, an electro-magnetic clutch for connecting the motor

with the shaft, and an electrical control comprising a circuit including the clutch, circuits including the respective electro-magnetic means of the power switch, relays individually energizable to close either circuit of said power switch electro-magnetic means and in each instance the clutch circuit, and a holding circuit completed by either relay for maintaining the energization of the respective relay and thus the closure of said circuits.

9. A mill control comprising an electro-magnetic clutch, a driving motor, a power switch and power circuit for the motor, electro-magnetic means for actuating the switch and controlling the flow of current to the motor, and an electrical control comprising separate circuits respectively including the clutch, motor and electro-magnetic means, a relay energizable to complete the clutch circuit, and a breaker switch closed by the action of the clutch to close the circuit of said electro-magnetic means for the closure of the power switch and power circuit.

10. In a rolling mill having a working roll and a pair of supporting rolls; a set of adjusting mechanism for the ends of the supporting rods, brakes by which each set of adjusting mechanism is held immovable when said mechanism is inoperative, and means for selectively operating either set of adjusting mechanism at the same time releasing the complementary brake, thus to effect an adjustment of the released ends of the supporting rods.

11. In a rolling mill having a working roll and a pair of supporting rolls; a set of adjusting mechanism for the ends of the supporting rolls, mechanically set and electro-magnetically releasable brakes by which each set of adjusting mechanism is held immovable when said mechanism is inoperative, and electrical selecting and actuating means for selectively operating either set of adjusting mechanism at the same time energizing the complementary brake to release the supporting rolls at one end for adjustment.

12. In a rolling mill having a working roll and a pair of supporting rolls; sets of screws applied to the ends of the supporting rolls to receive the separating thrusts thereof, operating means for selectively operating either set of screws to effect an adjustment of the supporting rolls at one end, and brakes for holding immovable the inoperative set of screws thus preventing screw drift of said inoperative set.

13. In a rolling mill having a working roll and a pair of supporting rolls; sets of screws applied to the ends of the supporting rolls to receive the separating thrusts thereof, independent operating means to turn either set of screws, selective electrical means for actuating either operating means thus to adjust either end of the rolls, and mechanical-

ly set but electro-magnetically releasable brakes for the respective operating means, one of the brakes holding one set of screws from drifting while the other brake is energized and released during a period of adjustment of the other set of screws.

14. A rolling mill comprising a working roll and supporting rolls therefor, actuating means for shifting an end of the supporting rolls either in similar or diverse directions, mechanical means for operating the actuating means, electrical means for controlling said mechanical means, said electrical means including a forwardly and reversely rotatable motor, and a device operated uni-directionally during either direction of rotation of the motor to limit the period of activity of the electrical means hence that of the mechanical means.

15. The combination of the supporting rolls of a rolling mill, individual means to receive and limit separating thrusts of the supporting rolls, an operating mechanism common to the assemblage of individual means, possessing instrumentalities for simultaneously causing any one of a variety of adjustments of said means, and a single control for said operating mechanism whence said instrumentalities are set in motion to bring about the adjustments.

16. The combination of the supporting rolls of a rolling mill, individual means to receive and limit separating thrusts of the supporting rolls, an operating connection for every one of the individual means, means joining said operating connections in one operating mechanism which means embodies instrumentalities for causing any one of a variety of adjustments simultaneously in all of said individual means, and an electrical control for imparting impulses to said operating mechanism agreeing with the adjustment intended.

17. In a rolling mill having a working roll and a pair of supporting rolls; abutment means receiving the separating thrusts of the supporting rolls, adjusting mechanism for feeding the abutment means either simultaneously in one or the opposite direction or simultaneously in diverse directions, and electrical means for selectively bringing the adjusting mechanism into action for performing the various feeds.

18. A rolling mill comprising a working roll and a pair of supporting rolls therefor, actuating means for shifting an end of the supporting rolls either in similar or diverse directions, and electrically controlled mechanical means in connection with said actuating means for effecting the various functions of the latter.

19. A rolling mill having a working roll and a pair of supporting rolls; abutment means for each of the supporting rolls, adjusting mechanism for feeding the abutment

means either simultaneously in one or the opposite direction or simultaneously in diverse directions, and electrical control means being selectively operative to actuate that component of said mechanism to perform the selected corresponding feed.

CLARK WHITE.
